UNITED STATES PATENT OFFICE

2,558,653

GENERATOR FOR ELECTRIC PULSATIONS
OF AUDIO-FREQUENCY

Edward M. Jones, Cincinnati, Ohio, assignor to
The Baldwin Company, Cincinnati, Ohio, a cor-
poration of Ohio

Application August 6, 1949, Serial No. 108,946

21 Claims. (Cl. 84—1.18)

1

My invention relates to generators for tones and voices useful in electric musical instruments, and in particular to photoelectric generators for such tones and voices.

One of the objects of the invention is the provision of a photoelectric tone generator as a single, self-contained unit, capable of producing all of the tones required in the range of an electric musical instrument of the keyboard variety. It is an object of my invention to provide a self-contained generator of this class capable of producing a wide variety of voices. A generator assembly which, as a self-contained unit, is capable of producing in a photocell a wide range of tones and tone colors I hereinafter refer to as a complete generator.

It is an object of my invention to provide a complete generator as an individual, self-contained unit, which is simple and inexpensive.

It is an object of my invention to provide a complete generator which contains all of the moving parts and motive means required in the production of the said tones and tone colors, the complete generator requiring only connection to the keys of a keyboard instrument and the stops thereof, together with electrical connections to a power source and to one or more amplifiers and loud speakers. Thus, it is an object of my invention to provide a complete generator which can be installed and replaced as a unit in an electrical musical instrument.

It is an object of my invention to provide a complete generator with a minimum of moving parts.

It is an object of my invention to provide a complete generator which is protected from extraneous influences including dust and dirt which would interfere with its operation.

It is an object of my invention to provide a complete generator in which the replacement and repair of individual parts is greatly facilitated.

These and other objects of my invention which will be set forth hereinafter or will be apparent to one skilled in the art upon reading these specifications, I accomplish by that construction and arrangement of parts of which I shall now describe an exemplary embodiment. Reference is made to the accompanying drawings wherein:

Figure 1 is a top plan view of my complete generator with certain parts of the casing broken away.

Figure 2 is a vertical sectional view of my complete generator taken along the section line 2—2 of Figure 1.

Figure 3 is an elevational view of my complete generator.

2

Figure 4 is a top plan view of simplified and semi-diagrammatic character of a base and shutter plate which I may employ.

Figure 5 is a partial sectional view taken along the line 5—5 of Figure 4 and showing a mode of actuating a tone color shutter.

Figure 6 is a partial sectional view through my pitch disc showing one mode of attachment of an armature element thereto.

It has hitherto been understood that if light from a source is broken up into spaced, moving beams following each other at an audio frequency corresponding to a note of the musical scale, it is possible to produce a voice or voices of any desired timbre by causing the moving beams of light to pass through wave form representations whereby they are modified as to harmonic content before the beams are caused to impinge on a photoelectric cell. The wave form representations have a length equivalent to the spacing on centers of the moving beams of light; there may be a plurality of wave form representations in consecutive order so that a plurality of the beams may be simultaneously modified for the purpose of admitting more light to the photoelectric cell and of smoothing out sporadic variations in the several wave form representations; and the series of wave form representations for modifying the several beams will be optically limited in extent so that as one beam begins to be modified by the representations, another leaves them to avoid in the produced tones alterations of the harmonic content represented by the wave forms. Moving beams of light will be provided for all of the desired frequencies within the range of the instrument; wave form representations for modifying the various sets of moving beams will be provided for each voice throughout the range of frequencies desired for that voice; and different sets of wave form representations throughout the range of the instrument or such portions of that range as may be desired, will be provided for each of the voices desired in the instrument, with arrangements for causing the several sets of moving beams to traverse these various wave form representations selectively or in desired combinations. These principles are employed in the generator structure herein described. Theoretically, the principles outlined above when translated into a physical structure should provide an inexpensive and simple generator for musical tones for use in keyboard instruments, as compared with other types of generators, say electromechanical, or thermionic. The great mass of complex electrical wiring in instruments using such other forms of generators is of course eliminated. The

tones, selected in accordance with the actuation of the playing keys, and modified as to voice in accordance with the actuation of stop tabs, are collected at the photocell; and it is only necessary to amplify and translate into sound the output of the photocell by means of a suitable amplifier and loud-speaker system. However, the theoretical advantages of this type of structure have not hitherto been attained in practice. The proposed assemblies have been complicated and unwieldy, have included mechanical coupling problems substantially as difficult as the electrical wiring problems of instruments using other types of generators, and in most instances have contemplated duplications of apparatus even for the production of that range of tones and voices required in a single manual instrument. Furthermore, the assemblies of apparatus hitherto proposed have been highly complex, liable to come out of adjustment, susceptible to failure in operation due to mechanical damage or the accumulation of dust and dirt, and have been difficult to assemble, disassemble and repair.

In the apparatus hereinafter described, I provide a complete generator assembly as a self-contained unit, sealed against access of dirt and dust, having but one driven moving part, of simple and inexpensive construction, with all parts easily accessible for repair or replacement, and with the whole unit readily removable should this be required. In this way, and in others which will be set forth hereinafter, I have obtained a structure wherein the theoretical advantages of the photoelectric type of operation can be fully realized.

The self-contained, complete generator unit hereinafter described can readily be made to produce all of the frequencies desired throughout the entire range of the instrument including high frequencies which may be desired primarily for coupling purposes. It may, indeed, be made to contain all of the frequencies required for a single keyboard plus a number of other frequencies which may be the same or may be octavely related, and which are appropriate for use, for example, in connection with a pedal keyboard. It is possible by varying the shutter arrangement to provide a single complete generator in accordance with my pattern which will serve more than one manual of an organ type instrument together with a pedal keyboard; but in the more elaborate double manual instruments where a great variety of different voices may be desired, it is readily possible to install two of my complete generating units connecting one with each of the manuals, and both with the pedal keyboard or portions thereof. Due to the inexpensive character of my assembly, this may readily be done without unduly increasing cost.

Briefly, in the practice of my invention I provide a main or base plate on which all other elements of the assembly are mounted, either directly, or by means of housing elements which engage the base plate and serve as a complete dust-tight cover for all of the active elements of the structure. The main or base plate of the apparatus is perforated for the passage of light. A source of light is located upon one side of it, and a photoelectric cell is located upon the other. Preferably the base plate is a shutter plate; and I prefer to employ a type of shutter construction in accordance with the general principles set forth in the copending application of John F. Jordan, entitled Shutter Mechanism, Serial No. 45,897, filed August 24, 1948, and now Patent No. 2,506,599.

In this copending application, Jordan described a structure having the advantage of including a very large number of shutter openings and shutters in a very small space, together with additional, or common shutter means whereby light from the source could be permitted to pass through any one or more of various series of primary light openings extending throughout the full tonal range or such portions thereof as may be desired, the last mentioned shutter means serving to select the voices as will hereinafter be made clear. The Jordan shutter plate comprised in an exemplary form, a disc-like member such as that illustrated diagrammatically at 1 in Figure 4 of this application. One surface of the plate is provided with a series of closely spaced grooves 3 in each of which is placed a wire element 4. The grooves are deep enough to contain the wire elements, and have a width substantially double that of the thickness of the wire elements. At one side of each of the grooves a deeper groove is cut, substantially half the width of the main groove. Channel-like configurations as at 6 are molded or cut into the other side of the shutter plate. They intersect the last mentioned, narrow, deeper grooves and thus provide series of light openings indicated in Figure 4 at 7. The wires 4 lying in the main grooves are adapted to cover or uncover these light openings; and they do this by flexing in response to either a push or pull exerted on the wires longitudinally as may be desired, one end of the wires being anchored as at 8. The channels 6 may be arranged radially or otherwise; but they traverse either the entire series of grooves or desired groups thereof; and there will be located in connection with each of the several series of light openings 7, a series of wave form representations as hereinafter set forth. Figure 4 is diagrammatic in that the number of wires and main grooves has been diminished for the purpose of a simplified showing. I have found it readily possible to provide in a shutter plate having a diameter of approximately fifteen inches a series of grooves great enough in number to accommodate all of the 73 notes desired for a single-manual organ, or all of the 61 notes desired for a given manual in a two-manual organ plus 12 or 13 others, as may be desired for connection with a pedal manual. The shutters themselves are simply operated by pushing or pulling upon the wires 4; and this is most conveniently done by providing Bowden transmissions, so-called, in connection with each. These transmissions comprise inner wires 4a, connected to the wires 4, in sheaves 9 anchored as at 9a. The grooves on the one side of the plate are interrupted in an area indicated generally at 10; but the rim of the plate may be continued as at 11. The sheaves 9 of the Bowden transmissions 60 may be passed through holes 12 in this rim. The Bowden transmissions may be prolonged as desired, and only require connection directly or indirectly with the playing keys of the instrument for actuation. It will be noted that the actuation 65 of a single wire will open up a plurality of apertures in the shutter plate, say one for each of the voice channels or slots 6. In this way, voices may readily be combined in my instrument.

Each of the voice channels or slots 6, will, as 70 shown in Figure 5 be provided with a hinged shutter 13, which also may be actuated by a wire 14 passing through a sheave 15 and forming a Bowden transmission. These last mentioned Bowden transmissions are initially located with 75 the stop shutter devices 13 on the under side of

my plate 1. In the space 10, however, I may provide an opening 16 through which the stop transmission elements 15 may be brought into the space 10 on the upper side of the shutter plate and then lead therefrom through perforations 17 in the rim 11, as shown in Figure 1. Again as shown in Figures 2 and 3 the transmissions 15 may be brought through transverse perforations in a channel engaging an edge of the lower can or housing hereinafter described. The Bowden transmissions 15 require only to be connected directly or indirectly with the stop tabs of the musical instrument, as will be understood. It will be clear that, when a voice shutter 13 is open, light responding to any of the frequencies for which there is a groove on the shutter plate traversed by the voice slot will be allowed to pass through one or more of the light openings 7 depending upon the actuation of one or more of the wires 4 by the playing keys of the instrument.

Juxtaposed to the shutter disc which I have been describing, there will be a plate or disc having concentric series of light openings in it, one for each of the frequencies desired, this disc, hereinafter called the pitch disc, is indicated at 18 in Figures 1 and 2. The pitch tracks thereon are diagrammatically indicated at 19 in Figure 1. Also juxtaposed to the shutter plate there is a voice disc (20, in Figure 2) which will bear wave form representations in a plurality of series, a series corresponding to each of the voice channels or slots 6 hereinabove described.

The specific construction of the shutter plate herein above described is not a limitation upon the present invention. The shutter plate may be modified as specifically set forth in my copending application entitled Method and Means for Producing Tones and Voices Photo-Electrically, Serial No. 117,239, filed September 22, 1949, wherein specific provision is made for octave coupling by means of the wires constituting the shutter elements, and wherein particular arrangements of the voice slots 6 are set forth and claimed.

Also, particular arrangements of the pitch tracks on the pitch disc 18 and the voicing representations on the voice disc 20 are not limitations on the present invention. Preferably their arrangement is that set forth in my copending application referred to above. The teachings of the present application relate to the novel combination and mechanical arrangement of elements as hereinafter taught and claimed, irrespective of variations in the physical details of the elements themselves, excepting as these may be included in the appended claims.

As indicated, the shutter plate 1 is the base plate or main plate of my construction. It is designed to be supported as such in the console of a musical instrument in any way, and on any particular means desired. To this end I have shown, in an exemplary fashion, ears formed on the plate for mounting purposes. Other means may be substituted as will be apparent, such as mounting brackets bolted to the plate, or the like.

Centrally of the shutter plate 1, I provide a bearing holder 22. The pitch disc 18 (usually and preferably a plate of glass, the pitch tracks being photographic representations thereon) is provided with a central perforation engaged by a hub 23 and a clamping flange 24. The hub 23 has a central, downwardly depending shaft 25. There is a thrust bearing, preferably a ball bearing 26, located between the hub 23 and the bearing holder 22; and at the lower end of the bearing holder there is a centering ball bearing in-

dicated at 27. The pitch disc, mounted as described, is the only driven element in my structure. The proportioning of the parts is such that the pitch disc is maintained parallel to and in close proximity to the shutter plate 1; but it will be seen from Figure 2 that the voice disc 20 rests directly on the shutter plate, its centered position being maintained by the bearing holder 22 which engages a central perforation in the voice disc 20. The voice disc 20 is also preferably a disc of glass, bearing voice representations which are photographic in nature. That the sets of voice or timbre representations on the voice disc 20 correspond in position to the voice channels or slots 6 will be clear without special illustration. The voice disc 20 may serve to maintain the wires 4 in the slots 3, as shown, or separate means may be provided for this purpose. Clamping means for the voice disc (not shown) may be provided to maintain its radial position.

The remaining apparatus elements going to make up my complete generator assembly are mounted or supported from the base plate 1 by means of housing elements or "cans." There is an upper can indicated generally at 28 and a lower can 29. These cans may be formed of sheet metal or other suitable material. Both are generally circular in shape excepting that they are generally flattened at one side as at 30 and 31. The upper can, however, has an extension indicated at 32 so that it is able completely to house the pitch disc 18. This extension may be integral with the upper can, or as shown, it may be formed as a separate member of any suitable construction, such, for example, as a die casting, and provided with a lower rim 33 responding to the rim 11 on the plate, and with side and top channels 34 and 34a to accept edge portions of the can 28, with a packing material to make the joints dust-tight.

There are various ways in which the cans may be attached to the plate. The upper can may be formed with a peripheral flange corresponding to the upper side of the rim 11 on the base plate 1. It may be held to the rim by means of bolts or otherwise, and if desired a gasket may be placed between the flange and rim so as to further the dust-tightness. The lower can 29 may be similarly shaped and fastened. However, I provide merely to rabbet the edges of the plate 1 for the acceptance of contacting edges of the cans, as most clearly shown in Figure 2, fastening the can edges in place by means of screws. Non-contacting edges of the upper can 28 are held, as above noted, in the channels 34 and 34a of the extension element 32. To accept the edge of the flattened portion 31 of the lower can 29, I prefer to mold or machine a channel 36 on the underside of the plate 1.

The lower can 29 contains a light source 37, usually and preferably in the form of an incandescent bulb. The bulb has a socket 38 which is preferably mounted in a removable housing element 39 extending through the wall of the lower can and provided with fins 40 for heat dissipation purposes. The front end of the housing 39 may be formed as at 41 to shield the shutter plate 1 from the direct rays of the lamp 37. Means for adjusting the position of the lamp 37 within the housing 39 may also be provided as desired. The direct rays of the lamp 37 pass downwardly and impinge upon a reflector 42. This reflector is half of a parabolic reflector which may be made of metal or silvered glass and is mounted in the lower can 29 by means of

suitable brackets 43 and padding 44. The parabolic reflector alters the direction of the light rays fanning downwardly from the bulb 37 and produces a series of parallel rays moving upwardly as indicated by the arrows in Figure 2 to pass through the openings in the shutter plate 1 and the representations on the voice and pitch discs 20 and 18. These rays pass upwardly to another half of a parabolic reflector, indicated at 45, mounted in the upper can 28 on brackets 46 and padding 47, and serving to focus the rays which pass through the shutter plate 1, voice disc 20 and pitch disc 18 on a photocell indicated at 48 in Figure 2. The mounting of the photocell will hereinafter be described.

The pitch disc in my structure is preferably directly driven by electromotive means. I prefer, but am not limited to, an eddy current motor. I provide the pitch disc 18 with a peripherally, up-standing armature element indicated at 49 in Figure 6. This is made up of convolutions or windings of some non-magnetic metal such as copper or aluminum. It may be fastened to the periphery of the voice disc in any suitable way. One way, which I prefer, is illustrated in Figure 6. The convolutions making up the armature 49 are riveted or otherwise fastened together so that the armature will maintain its annular form. One of the convolutions 49a is carried downwardly beyond the others; the edge of the disc 18 is bevelled as shown, and the projecting portion of the outer convolution is upset or bent over against the bevelled edge of the disc, thus firmly fastening the armature to the disc.

The remaining elements of the eddy current motor which I prefer to use comprise an inner structure having a C-shaped core 50 and a winding 51 (see Figure 1). This structure is supported from the extension 32 of the upper can by means of bolts 52 and sleeves, in a position such that the ends of the C-shaped core 50 are in close proximity to the armature 49. There is also an outer motor element comprising an E-shaped core 53 and winding 54. These elements are supported on and housed by the upper can extension 32; this extension having a protuberance 55 for the purpose. The motor element is mounted therein by means of bolts 56 so that the ends of the core legs are in close proximity, as shown, to the armature 49. The coils 51 and 54 will be energized by alternating current in any way desired. Speed control and provisions for variation of the speed to provide a vibrato, may be incorporated in this structure as set forth in the copending application of Edward M. Jones and George F. Williamson entitled Systems for the Production and Use of Electric Pulsations for Control Purposes, Serial No. 117,240 filed September 22, 1949.

The photocell 48 may be mounted in a suitable socket 57 on a bracket 58 affixed to the inside of the flattened portion 30 of the upper can 28. The socket will be so positioned as to support the photocell 48 at the focus of the rays from the upper parabolic mirror 45. The bracket 58 may also support elements indicated generally at 59, which elements may include a preamplifier or other circuit devices useful in connection with the photocell 48 and such speed control circuit elements as may be desired in connection with the windings 51 and 54 of the eddy current motor used for driving the pitch disc.

In Figure 1, I have shown at 70 a speed-control track 70 and a vibrato track 71 on the pitch disc 18. Light from the source 37 passes through

appropriate openings in the plate 1, thence through these tracks, and impinges on another photocell 72 which is also mounted on the bracket 58.

5 The various connections from the electrical elements in the upper can 28 may be brought out to a pronged connector 60 (or a socket) mounted in the flattened portion 30 of the upper can. In this way the upper can may be entirely disconnected, electrically, if it becomes desirable to remove it or to remove the complete generator from the instrument. The bulb 37 is provided with leads 61 for the application of power and these may be provided with a plug-in connection to a source of power. Also the housing 39 for the light source may be removed as such from the lower can, and without removing the lower can, since it is held thereto by bracket means 62. Either can may be removed for repair or replacement without disturbing any other part of the apparatus, as will be evident. The connections to the playing keys and to the stops run only to the base plate 1 as will also be clear; but the complete generator may be removed from the console of an instrument by disengaging these connections and disengaging the ears 21 from the supporting means within the console.

15 The apparatus assembly is simple; it has as indicated above only one driven part namely the pitch disc 18; it can be made inexpensively but with great accuracy; it can be very small in size for the number of frequencies and voices producible by it; it is completely enclosed and dust-tight although readily accessible for repair or replacement, and it requires no electrical wiring excepting for connections to a source of power and to an amplifier and loud speaker system.

20 Modifications may be made in my invention without departing from the spirit of it. Having thus described my invention in an exemplary embodiment, what I claim as new and desire to secure by Letters Patent is:

1. In a generator, a base plate having openings 45 for the passage of light, a bearing holder mounted substantially centrally on said base plate, a shaft mounted on bearings in said bearing holder, a hub on said shaft and a pitch disc mounted on said hub and lying in proximity to and adjacent a surface of said base plate.

2. In a generator, a base plate having openings 50 for the passage of light, a bearing holder mounted substantially centrally on said base plate, a shaft mounted on bearings in said bearing holder, a hub on said shaft and pitch disc mounted on said hub and lying in proximity to and adjacent a surface of said base plate, and means for rotating said pitch disc supported from said base plate.

3. In a generator, a base plate having openings 60 for the passage of light, a bearing holder mounted substantially centrally of said base plate, a shaft mounted on bearings in said bearing holder, a hub on said shaft and a pitch disc mounted on said hub and lying in proximity to and adjacent a surface of said base plate, and means for rotating said pitch disc supported from said base plate, and comprising an annular armature mounted substantially peripherally on said pitch disc and an electromagnet acting on said armature.

4. The structure claimed in claim 3 wherein 65 housings are removably attached to either side of said base plate, one of said housings containing and supporting a light source and the

other containing and supporting a photoelectric cell.

5. The structure claimed in claim 3 wherein housings are removably attached to either side of said base plate, one of said housings containing and supporting a light source and the other containing and supporting a photoelectric cell, said light source and photoelectric cell being in substantial axial alignment with said shaft, and said housings also containing reflectors serving to pass light from said light source through openings in said main plate and to focus the said light on said photo cell.

6. The structure claimed in claim 5 wherein said housings have flattened sides, wherein said light source is mounted in a heat dissipating fixture affixed to the flattened side of one of said housings.

7. The structure claimed in claim 5 wherein said housings have flattened sides, wherein said light source is mounted in a heat dissipating fixture affixed to the flattened side of one of said housings, and wherein said electromagnet constitutes together with said armature an eddy current motor and comprises a C-shaped core and winding mounted interiorly of said armature and an E-shaped core and winding mounted exteriorly thereof, both cores being mounted to the housing supporting said photoelectric cell and included therein, said housings forming with said main plate a dust-tight construction.

8. The structure claimed in claim 5 wherein said housings have flattened sides, wherein said light source is mounted in a heat dissipating fixture affixed to the flattened side of one of said housings, and wherein said electromagnet constitutes together with said armature an eddy current motor and comprises a C-shaped core and winding mounted interiorly of said armature and an E-shaped core and winding mounted exteriorly thereof, both cores being mounted to the housing supporting said photoelectric cell and included therein, said housings forming with said main plate a dust-tight construction, said annular armature being substantially cylindrical in formation and extending substantially normal to the periphery of said pitch disc.

9. The structure claimed in claim 5 wherein said housings have flattened sides, wherein said light source is mounted in a heat dissipating fixture affixed to the flattened side of one of said housings, and wherein said electromagnet constitutes together with said armature an eddy current motor and comprises a C-shaped core and winding mounted interiorly of said armature and an E-shaped core and winding mounted exteriorly thereof, both cores being mounted to the housing supporting said photoelectric cell and included therein, said housings forming with said main plate a dust-tight construction, said annular armature being substantially cylindrical in formation and extending substantially normal to the periphery of said pitch disc, and being laminated in construction and formed from a winding of non-magnetic strip metal, certain of the convolutions thereof engaging a surface of said pitch disc and at least one convolution extending beyond said surface and crimped against a beveled edge of said pitch disc whereby to fasten said armature to said pitch disc.

10. The structure claimed in claim 2 wherein said main plate is a shutter plate having substantially concentric grooves in its surface lying adjacent said pitch disc, wires lying in said grooves, and acting as shutter elements for said

light openings which open into said grooves, the said surface of said main plate having a depressed portion formed by an interruption of said grooves and terminating outwardly in a raised rim, said wires being connected to actuating wires which change direction in said depressed portion and pass outwardly peripherally of said plate through openings in said rim, one end of each of said first mentioned wires being anchored to said main plate.

11. The structure claimed in claim 2 wherein said main plate is a shutter plate having substantially concentric grooves in its surface lying adjacent said pitch disc, wires lying in said grooves, and acting as shutter elements for said light openings which open into said grooves, the said surface of said main plate having a depressed portion formed by an interruption of said grooves and terminating outwardly in a raised rim, said wires being connected to actuating wires which change direction in said depressed portion and pass outwardly peripherally of said plate through openings in said rim, one end of each of said first mentioned wires being anchored to said main plate, said actuating wires where they pass through said rim and therebeyond being surrounded by sheaths.

12. The structure claimed in claim 2 wherein said main plate is a shutter plate having substantially concentric grooves in its surface lying adjacent said pitch disc, wires lying in said grooves, and acting as shutter elements for said light openings which open into said grooves, the said surface of said main plate having a depressed portion formed by an interruption of said grooves and terminating outwardly in a raised rim, said wires being connected to actuating wires which change direction in said depressed portion and pass outwardly peripherally of said plate through openings in said rim, one end of each of said first mentioned wires being anchored to said main plate, said actuating wires where they pass through said rim and therebeyond being surrounded by sheaths, and a voice disc lying against the grooved surface of said main plate and substantially closing the grooves therein.

13. The structure claimed in claim 12 wherein the said substantially concentric grooves have narrower grooves extending inwardly from their bottom portions and wherein said last mentioned grooves are intersected by channels formed in the opposite face of said base plate so as to intersect said grooves, thereby providing said light openings.

14. The structure claimed in claim 12 wherein the said substantially concentric grooves have narrower grooves extending inwardly from their bottom portions and wherein said last mentioned grooves are intersected by channels formed in the opposite face of said base plate so as to intersect said grooves, thereby providing said light openings, and wherein said channels are provided with shutters operated by wire-and-sheath transmissions, and wherein said last mentioned transmissions pass outwardly from said plate through a dust-tight exit.

15. The structure claimed in claim 12 wherein the said substantially concentric grooves have narrower grooves extending inwardly from their bottom portions and wherein said last mentioned grooves are intersected by channels formed in the opposite face of said base plate so as to intersect said grooves thereby providing said light openings, and wherein said channels are provided with shutters operated by wire-and-sheath transmis-

sions; and wherein said last mentioned transmissions pass outwardly from said plate through a dust-tight exit, and in which said pitch disc and voice disc are members of transparent material bearing photographic representations respectively of light slots arranged concentrically in accordance with the pitch requirements of a musical scale and located opposite said light openings in said main plate, and voicing representations aligned with the series of openings formed in connection with said channels.

16. In combination for the purpose described a shutter plate constituting a mounting plate, a voice disc supported by said shutter plate, a pitch disc adjacent said voice disc and rotatively mounted on said shutter plate, housings detachably mounted to either side of said shutter plate, driving means for said pitch disc mounted on one of said housings, a light source and a photoelectric cell mounted respectively on said housings, said housings having a dust-tight relation with said shutter plate, and shutter operating elements passing from said shutter plate through peripheral openings therein whereby to preserve said dust-tight construction.

17. The combination claimed in claim 16, including a speed control track on said pitch disc and a second photoelectric cell mounted in the housing containing said first mentioned photoelectric cell, said second cell being aligned with said track.

18. In combination for the purpose described, a disc-like shutter plate constituting a mounting plate, a bearing holder mounted substantially centrally on said shutter plate, a pitch disc of lesser diameter than said shutter plate and having a shaft mounted in bearings in said bearing holder, a voice disc supported by said shutter plate, driving means for said pitch disc, a light source and a photoelectric cell, housings mount-

ed to either side of said shutter plate and enclosing all of the above recited elements excepting for portions of said shutter plate and coacting with said shutter plate to form a dust-tight construction and strand-like shutter operating elements entering said dust-tight construction substantially at the level of said shutter plate.

19. In a generator, a base plate, a pitch disc journaled for rotation on said base plate, an annular armature rim on said pitch disc, and electromagnetic driving means for said armature supported from said base plate.

20. In a generator, a base plate, a pitch disc journaled for rotation on said base plate and an annular armature rim on said pitch disc, said rim being of laminated construction, and non-rotatably fastened to the said pitch disc.

21. The structure claimed in claim 20 wherein said armature is substantially cylindrical in shape and extends substantially normal to the said pitch disc at the periphery thereof, the laminated construction of said armature being convolute, the edges of certain of the convolutions engaging a surface of the pitch disc and at least one convolution extending beyond said surface and crimped against another surface portion of said pitch disc.

EDWARD M. JONES.
